TELEPHONE STAND

Carol Hewitt Eubank, Greenwood, Ind., Donald Michael Genaro, Haworth, N.J., John Niel McGarvey, Drexell Hill, Pa., and Terry Brice Prince, Indianapolis, Ind., assignors to Bell Telephone Laboratories, Incorporated, Murray Hill, N.J.

Filed May 29, 1973, Ser. No. 364,718

Term of patent 14 years

Int. Cl. D14—03
U.S. Cl. D26—14 A

FIG. 1

FIG. 2

FIG. 3

FIG. 4

FIG. 5

FIG. 6

FIG. 7

FIG. 8

FIG. 1 is a perspective view showing the top, side, and a portion of the front of a first form of our new design for a telephone stand;

FIG. 2 is a side view of the first form of the telephone stand, the opposite side being essentially a mirror image of the side shown;

FIG. 3 is a top plan view of the first form of the telephone stand looking in the direction of line 3—3 of FIG. 2;

FIG. 4 is a rear view of the first form of the telephone stand;

FIG. 5 is a perspective view showing the top, side, and a portion of the front of a second modified form of our new design for a telephone stand;

FIG. 6 is a side view of the second form of the telephone stand, the opposite side being essentially a mirror image of the side shown;

FIG. 7 is a top plan view of the second form of the

telephone stand looking in the direction of line 7—7 of FIG. 6; and

FIG. 8 is a rear view of the second form of the telephone stand.

We claim:

The ornamental design for a telephone stand, substantially as shown and described.
